UNITED STATES PATENT OFFICE.

VINCENT CROCE, OF NEW YORK, N. Y.

BARREL.

1,192,869.

Specification of Letters Patent. Patented Aug. 1, 1916.

Application filed December 6, 1913. Serial No. 805,096.

To all whom it may concern:

Be it known that I, VINCENT CROCE, a citizen of Italy, residing at New York, in the county of New York and State of New York, have invented new and useful Improvements in Barrels, of which the following is a specification.

This invention relates to shipping and storing vessels and more particularly to collapsible or knock down barrels or like articles.

The principal object of the invention is to provide a device of this character which is constructed in such manner that it may be folded flat or rolled into compact form for return shipment or storage and which may be set up or knocked down in a comparatively short space of time.

Further objects of the invention will appear as the following description is read in connection with the accompanying drawing, which forms a part of this application, and in which:

Figure 1 is a side elevation. Fig. 2 is a detail side elevation, on an enlarged scale. Fig. 3 is a horizontal section showing the manner of connecting the staves in top plan view and also showing the means employed for preventing the bottom from bulging. Fig. 4 is a bottom plan view. Fig. 5 is a detail vertical sectional view.

Referring more particularly to the drawings, 1 represents a plurality of staves each one of which has attached thereto, by means of staples 2 or the like, a plurality of links 3 arranged upon the stave, one link at the lower end of the stave, one adjacent the upper end of the stave and one arranged at an intermediate point, all links extending transversely of the stave and being joined to similar links upon adjoining staves. Each stave is properly crooked to receive the top and bottom of the barrel, and the terminal ends of the chains, formed by connecting the links, may be secured together in any suitable manner but preferably by a link looped through one terminal of the chain and having its opposite end split to enable the link to be readily connected with, or disconnected from the opposite end of the chain with which the link is connected, the link being further provided with a stop shoulder in each side wall adapted to contact with the legs of a staple by means of which said links are connected to one of the

staves forming the barrel body, thus enabling the barrel to be set up or knocked down or the staves rolled into a small and compact package for storage or return shipment.

The heads and bottoms of the barrels are constructed alike, each of two semi-circular halves 4 and 5 being connected together upon their under sides by links 6 and having upon their upper sides the cross pieces 7 and 8, the former of which are secured to the half 4 while the latter is secured intermediate the two cross pieces 7 and to the half 5. The links 6 of the top are arranged upon the inner side of the barrel so that the top may be inserted in an angular position and then forced downwardly in the center to align the separate halves, the pieces 7 and 8 serving as limiting pieces to prevent movement of the top inwardly. The limiting pieces of the bottom are arranged upon the inside of the barrel so that a slight pressure upon the under side of the bottom when the barrel is empty will cause the bottom to fold in half for removal.

It will be noticed that as the cross pieces 7 and 8 are arranged upon the inside of the bottom that the weight of the material within the barrel cannot bulge the bottom outwardly but immediately upon entering the barrel the bottom may be bulged inwardly or folded so as to be removed from the staves. The top having the cross pieces arranged upon the outside limits the inward movement of the head when forced into position and permits its ready removal from the barrel.

What is claimed is:—

In a knockdown barrel, a body formed of staves, chains connected with the staves, a link looped through one end of each chain and provided with a split end whereby said links may be connected with the remaining ends of the chains, means for connecting said links with one of the staves in the barrel body, and shoulders formed in the side walls of said links and adapted to contact with the above mentioned means.

In testimony whereof I affix my signature in presence of two witnesses.

VINCENT CROCE. [L.S.]
